UNITED STATES PATENT OFFICE

109,387

DESIGN FOR AN EYESHADE

Martin Berg, New York, N. Y.

Application March 15, 1938, Serial No. 75,817

Term of patent 7 years

To all whom it may concern:

Be it known that I, Martin Berg, a citizen of Germany, residing at New York city, county and State of New York, have invented a new, original, and ornamental Design for an Eyeshade, of which the following is a specification, reference being had to the accompanying drawing, forming a part thereof.

I claim:

The ornamental design for an eyeshade, as shown.

MARTIN BERG.
